UNITED STATES PATENT OFFICE.

EDWARD E. BRADLEY, OF STONINGTON, CONNECTICUT, ASSIGNOR TO THE ATWOOD MACHINE COMPANY, OF SAME PLACE.

REELING-MACHINE.

SPECIFICATION forming part of Letters Patent No. 449,360, dated March 31, 1891.

Application filed January 11, 1890. Serial No. 336,649. (No model.)

To all whom it may concern:

Be it known that I, EDWARD E. BRADLEY, of Stonington, in the county of New London and State of Connecticut, have invented a new 5 and useful Improvement in Reeling-Machines, of which the following is a specification, reference being had to the accompanying drawings.

This invention may be applied to reeling- 10 machines for reeling various fibrous materials, and is especially adapted for reeling-machines for winding or reeling silk warp. In such machines there is employed a carriage which carries reeds and is commonly known 15 as the "reed-carriage," and which has a traverse motion imparted to it.

The improvement relates to the means of supporting and driving such carriage; also, to registering apparatus for registering the 20 amount of yarn that is wound, and to devices in connection with such registering apparatus to effect the stoppage of the machine after a certain determined length of yarn has been wound.

25 Figure 1 in the accompanying drawings represents a front elevation of the machine embodying my improvement. Fig. 2 represents a transverse vertical section taken close within the left-hand-side frame and viewed toward the 30 right. Fig. 3 represents a horizontal section of the parts at the left-hand side of the machine, taken in the line xx of Fig. 2, the parts exposed to view in said figure constituting the principal parts of the stop-motion. Fig. 35 4 represents a central transverse vertical section of the reed-carriage, the parts for supporting it, and its driving mechanism. Fig. 5 is a plan view of the parts shown in Fig. 4. Fig. 6 is a side view of a portion of the left- 40 hand end of the machine, including the registering mechanism. Fig. 7 is a plan corresponding with Fig. 6, showing the upper part of the framing in section in the line yy of Fig. 6. Fig. 8 is a plan view of a bell and its 45 striking mechanism employed in connection with the registering apparatus, as hereinafter described. Fig. 9 represents a vertical section of the mechanism for striking the said bell. Figs. 1, 2, and 3 are on the same scale. 50 Figs. 4, 5, 6, and 7 are on a larger scale, and Figs. 8 and 9 on a still larger scale.

Similar letters of reference designate corresponding parts in all the figures.

A A A' A' A² constitute the framing of the machine, A A being side frames or standards, 55 A' A' being ordinary girts or stretchers between the lower parts of the said side frames, and A² being a horizontal girt, which will be hereinafter more particularly described, between the upper front parts of the side frames. 60

B is the main shaft, to which power is applied for driving the machine, said shaft being supported in bearings in the upper parts of the side frames.

C is the traverse-screw, which serves to 65 support the reed-carriage D, as well as to produce the traverse movement thereof, the said screw being journaled in bearings in the side frames A A in such manner as to be capable of rotary motion, but to be confined 70 lengthwise.

E is the reel, which may be of ordinary construction, and the shaft E' of which is unsupported in bearings in the back part of the side framing. The reel derives motion, as shown 75 in Figs. 1 and 2, from the main shaft B through a pinion B' on the said shaft B, an intermediate spur-gear F, with which said pinion gears, and a spur-gear E² on the reel-shaft gearing with said intermediate gear F. 80 The latter gear turns freely on a stud F', secured to the left-hand side framing. The traverse-screw C also derives motion from the said gear F, before mentioned, through a train of gearing and shafts, as follows: G is a short 85 horizontal shaft, which turns freely in a box G', provided in the left-hand side framing. This shaft is provided with a spur-gear G², through which it receives motion from the gear F, the said shaft being also provided 90 with an endless screw G³, which engages with and drives a worm-wheel a, fast on the lower end of an inclined shaft a', which works in bearings a', secured to the side framing, and the upper end of which is furnished with a 95 bevel-gear a³, which gears with and drives a bevel-gear b, fast on the traverse-screw C. The traverse-screw produces the traverse of the carriage by its threads engaging with a worm-gear c on a shaft c', which works in 100 bearings in the said carriage, and on which is a spur-gear c², which gears with a fixed hori-

zontal toothed rack d , the said screw turning the said worm-gear, shaft, and spur-gear, and the spur-gear being thus caused to run along the rack, taking the carriage with it. The 5 said carriage D is supported upon the traverse-screw by means of two boxes e , (see Figs. 1 and 5,) provided on the said carriage, and which are bored to fit the exterior of the screw-threads, so that the screw may rotate 10 freely within the said boxes and the carriage may slide freely along the screw, as it is thereby caused to make its traverse in front of and parallel with the reel through the worm-gear c and spur-gear c^2 , as just described. It will 15 thus be seen that the screw supports the whole weight of the reel-carriage, as well as serves to produce the traverse movement thereof.

The carriage, except as to the provisions for supporting it and producing its traverse, 20 as above described, may be substantially like those common to reeling-machines. It is represented as provided, as is usual, with two reeds I I' and two parting-bars I^2 .

To prevent the carriage from swinging on 25 the traverse-screw and to assist the said screw in guiding it, a fixed straight guide d' (see Figs. 1, 2, and 4) is provided on the horizontal girt A^2 below and in front of the teeth of the rack d , and a flange d^2 is provided on the 30 lower part of the carriage to run against this fixed guide d' , the carriage being so balanced upon the screw that its weight will keep the said flange d^2 against the said guide. In order to provide for this guide being adjusted 35 parallel with the axis of the said screw, the girt A^2 has its ends adjustably secured to the side framing A , as shown in Fig. 6, by bolts d^4 , which pass through slots d^5 (see also Fig. 4) in flanges provided at the ends of the said 40 girt, the said flanges permitting the backward and forward adjustment of the ends of the said girt.

In order to provide for moving the carriage along the rack quickly by hand, a clutch f f' 45 is provided between the worm-gear c and the spur-gear c^2 of the carriage. The worm-gear c is fast upon the shaft c' , and the spur-gear c^2 is fast upon a hollow shaft c^3 , which works in a bearing c^4 in the carriage. The shaft c' 50 has a bearing in a hanger c^5 , (see Fig. 4,) affixed to the carriage and a bearing in the hollow shaft c^3 . The member f of the clutch is provided on or firmly secured to the worm-wheel c and fast to the shaft c' . The member f' of the clutch is fast to the spur-gear c^2 55 and hollow shaft c^3 . A hand-wheel c^6 is screwed to the hollow shaft c^3 of the spur-gear c^2 . On the end of the shaft c' of the worm-gear c there is a screw-thread c^7 , to which is 60 fitted a nut c^8 , which bears against the outer end of the hollow shaft c^3 . By screwing up this nut c^8 against the end of the said shaft c^3 the two members of the clutch are tightened 65 together and the spur-gear is made fast to the worm-gear, so that when the worm-gear is turned by the traverse-screw it causes the spur-gear to run along the rack. When the

nut c^8 is unscrewed, the clutch is loosened, and the spur-gear c^2 can be turned by the hand-wheel c^6 for moving the carriage along the 70 rack, the shaft c' and the worm-gear being thus free to turn, while the worm-gear runs freely along the threads of the screw, as upon a rack, without any effect.

H is a registering-wheel fitted to turn freely 75 on a fixed stud H' on the exterior of the left-hand side framing. This registering-wheel has upon its peripherical face a graduated scale, as shown in Fig. 7, representing yards or other measurements. It is also furnished 80 on its periphery at one side of the graduated face with teeth t , which engage, as best shown in Fig. 6, with an endless screw g on a shaft g' , arranged in bearings g^2 outside of the side frame, and which has on its forward end a 85 worm-gear g^3 , which gears with an endless screw g^4 on the shaft G , before described as forming part of the train of gearing for driving the traverse-screw. The said endless screw g^4 drives the worm-gear g^3 , shaft g' , and 90 endless screw g , and the latter drives the registering-wheel. The bearings g^2 for the shaft g' are not attached directly to the framing A , but are constructed on or secured to a hanger H^2 , which is pivoted at its front end to the 95 side frames by means of a pin h , and the rear end of which is capable of being lowered far enough to let the endless screw g out of gear with the teeth of the registering-wheel for the purpose of permitting the said wheel to be run 100 back by hand to the position for starting the measurement, which position is determined by a projection h' on the said wheel coming in contact, as shown in Figs. 6 and 7, with a fixed stop-finger h^2 , secured to the side framing. One edge of this projection h' is on the zero-line of the scale, and one edge of the finger h^2 serves as an index to the scale on the peripherical face of the registering-wheel and as a permanent starting-point for the registering-wheel. The rear end of the hanger H^2 110 is supported in a proper position to bring the endless screw g into gear with the teeth of the registering-wheel by means of a loaded lever h^3 , which is pivoted at h^4 to the side framing, 115 the said lever holding the said hanger up against a stop h^5 , secured to the side framing in such a position that the top and bottom of the thread of the endless screw g do not bind 120 against the bottoms and tops of the teeth of the registering-wheel. When it is intended to throw the endless screw g out of gear, the operator with one hand raises the loaded end of the lever h^3 , and thus permits the rear end 125 of the hanger to fall as far as necessary, while with the other hand he turns the registering-wheel to the zero position. When the registering-wheel is thus placed, the operator lets go the loaded lever, which throws the hanger H^2 up to its place against the stop h^5 . 130

The registering-wheel H is provided on its outer face with a number of projections i for the purpose of ringing a bell J every time a certain length of yarn has been reeled. In

the example of the invention represented one revolution of the registering-wheel registers three hundred and sixty yards of warp reeled, and there are nine projections *i* for ringing the bell, thus causing the ringing to take place after the reeling of every forty yards. The bell *J* is secured in a small frame *J'* (see Figs. 6, 8, and 9) by a screw *J*², which also serves the purpose of securing the said frame *J'* to the framing of the machine. The bell-hammer *J*³ swings on a fixed pin *j*, secured in the framing *J'*, and the shank of the hammer has on it a forward projection *j'*, which comes between the two fork-like prongs *j*² *j*³, provided on the hub of a trip-lever *J*⁴, which also turns freely on the pin *j*. The said lever *J*⁴ occupies a position to be struck by the projections *i* of the registering-wheel during the rotation of the latter. A light coil-spring *j*⁴ connects the hammer *J*³ with the frame *J'*, and so holds the hammer just clear of the bell, as shown in Fig. 6, while the trip-lever *J*⁴ is left free, the lower prong *j*³ of the fork of the lever then resting against the projection *j'* of the hammer, as shown in Fig. 9. The registering-wheel, while the reel is in operation, rotates in the direction of the arrow upon it near the ball in Fig. 6, and by its rotation the projections *i* are caused to come in contact with and depress the lever *J*⁴, the prong *j*³ of which is thus caused by its action on the projection *j'* on the hammer to raise the hammer, and at the same time to wind up and increase the tension of the spring *j*⁴, and when the projection passes the lever *J*⁴ the spring is caused to react upon the hammer and make it strike the bell. When the registering-wheel has been thrown out of gear by the machine and has been turned backward by hand to reset it to zero or the starting-point, as shown in Figs. 6 and 7, the projections *i* on the wheel, striking the lever *J*⁴, knock it upward without any action on the bell-hammer. During this last-described action the prong *j*² of the fork of the lever is arrested by the projection *j'* on the hammer to prevent the said lever from flying over out of an operative position.

In order to provide for the stoppage of the machine after a determined quantity or length of yarn has been reeled, I provide on the registering-wheel *H* a projecting finger *k*, for the purpose of operating a stop-motion by which the machine is thrown out of gear. In order to make this finger variable in its action to stop the machine after any determined quantity of yarn has been wound, I construct this finger *k* on an arm *K*, which is pivoted centrally to the registering-wheel, and which may be secured by a clamping-screw *k*', passing through it to either one of a number of tapped bosses *k*², provided on the outer face of the said wheel. To provide for a closer adjustment than could be provided by simply shifting the arm *K* and the clamping-screw *k*' from one boss *k*² to another, the said arm is constructed, as shown in Fig. 6, with a slotted

segment *k*³, said screw *k*' passing through the slot in this segment. A stop-motion is represented in Figs. 1, 2, and 3, and is also partly represented in Figs. 6 and 7. In Figs. 1 and 7 the pinion *B*', employed on the driving-shaft to give motion, as hereinbefore described, to all parts of the machine, has provided on it or attached to it one member *l* of a clutch, the other member *l*' of which is firmly secured upon the said shaft. The pinion *B*' is fitted loosely to the said shaft, and is, with its attached member *l* of the clutch, capable of being moved lengthwise on the shaft by means of a forked lever *L*, which works on a fixed fulcrum *m*, secured to the framing of the machine. The lower end of this lever is connected by a short connecting-link *m*' with a horizontal lever *M*, which is fulcrumed at *M*' on one of the lower girts *A'* of the framing. This lever *M* is connected with the other lower girt *A* by means of a spring *m*², which exerts a constant tendency to pull the said lever in such direction that by its action on the upright lever it will cause the latter to act upon the pinion *B*' and throw its attached member *l* of the clutch out of gear from the other member *l*' of the clutch which is fast to the main shaft. The pinion *B*' and its attached member *l* of the clutch are held in gear against the pull of the spring *m*² by means of a hook *N* on the lower end of a nearly upright shaft *N*', which is fitted to bearings *n*, secured to the framing, the said hook engaging with a projection *m*³ on the lever *M*, as shown in Fig. 3. This shaft *N*' has applied, as shown in Figs. 1 and 2, between it and the upper bearing *n* a coil-spring *n*', which tends to throw the hook *N* into engagement with the projection *m*³. On the upper end of the said shaft *N*' is an arm *N*², which projects outward from the side of the framing within reach of the finger *k* on the registering-wheel. When during the rotation of the registering-wheel the finger *k* is brought into contact with the projecting arm *N*², it is caused by its action on said arm and the shaft *N*' to throw back the hook *N* from the projection *m*³. The spring *m*², being then allowed to act upon the lever *M* and through it upon the lever *L*, shifts the pinion *B*' and its attached member *l* of the clutch out of gear with the member *l*' of the clutch, which is fast on the main shaft, and the machine stops.

What I claim as my invention, and desire to secure by Letters Patent, is—

1. The combination, with the reel, of a traverse-screw for moving a reed-carriage lengthwise of the reel, fixed bearings in which said screw is journaled, and a reed-carriage supported on said screw and free to slide lengthwise thereof, substantially as herein set forth.

2. The combination, with the reel and the supporting-frame therefor, of a fixed toothed rack arranged lengthwise of the reel, a traverse-screw journaled in the said frame parallel with said rack, mechanism, substantially as described, for turning said screw, a reed-

carriage supported on said screw and free to slide thereon independently of the rotation thereof, a shaft journaled in said carriage, a worm-gear on said shaft engaging with said screw, and a spur-gear on said shaft gearing with said rack, substantially as and for the purpose herein set forth.

3. The combination, with the reel, the traverse-screw, and mechanism, substantially as described, for operating them, and the fixed rack, of the reed-carriage supported on said screw, the shaft journaled in said carriage, the worm-gear gearing with said screw, and the spur-gear gearing with said rack, one of said gears being fast and the other loose on said shaft, a clutch and means for engaging and disengaging the same between said spur-gear and worm-gear, and a hand-gear fast to said spur-gear, all substantially as herein described, to provide for traversing the carriage either by means of the screw or by hand.

4. The combination, with the reel and the end frames or standards, of a traverse-screw and journal-boxes therefor supported by said frames or standards, a reed-carriage supported on said screw and free to slide thereon independently of the rotation thereof, a stationary girt carrying a toothed rack between said frames or standards, a shaft on said carriage, a spur-gear and a worm-gear on said shaft gearing, respectively, with said rack and screw, and a guide on the said girt to direct the carriage on the traverse-screw in proper relation to the reel, all substantially as herein set forth.

5. A registering-wheel for a reeling-machine having on its peripherical face a scale of measurements and having teeth on its periphery for driving it, in combination with a drive-shaft having a swinging movement toward and away from the periphery of the wheel and provided with a worm adapted to engage the teeth on the periphery of the wheel, substantially as herein described.

45 6. The combination, with a reel, a drive-

shaft, a register-wheel, gear for transmitting the motion of the said shaft to the reel, and worm-gear for transmitting the motion of said shaft to the registering-wheel, the worm forming a part of said worm-gear having a swinging movement toward and away from the registering-wheel, of a stop-motion between the registering-wheel and the aforesaid drive-shaft and a finger carried by said registering-wheel for disengaging said stop-motion after a given quantity of warp-thread has been reeled, substantially as set forth.

7. The combination, with the registering-wheel of a reeling-machine, having on its periphery a scale and a projection at the zero-line of said scale, of a fixed finger on the framing of the machine, substantially as described, the said finger serving as a stop to the said projection, a permanent starting-point for the wheel, and an index to the scale, as herein set forth.

8. The combination, with the main shaft B, the traverse-screw C, and the bevel-gear b thereon, and the registering-wheel H, having a scale on its peripherical face and teeth t on its periphery, of the shaft G, geared with the main shaft B, substantially as described, the two intermediate shafts g' a' between said shaft G and the registering-wheel H, and traverse-screw C, respectively, the two endless screws g⁴ G³ on the said shaft G, the worm-wheel g³ on the said shaft g', gearing with the endless screw g⁴, the endless screw on the shaft g', gearing with the teeth t on the registering-wheel H, the worm-wheel 80 a on the shaft a', gearing with the endless screw G³, and the bevel-gear a³ on the said shaft a', gearing with the bevel-gear b on the traverse-screw, substantially as herein set forth.

EDWARD E. BRADLEY.
